UNITED STATES PATENT OFFICE.

ISAAK JACOBSON, OF SPANDAU, GERMANY, ASSIGNOR TO BRUNO MULLER, OF GORLITZ, GERMANY.

TALKING MACHINE.

Application filed May 29, 1924, Serial No. 716,789, and in Germany June 2, 1923.

This invention relates to a talking machine of the kind in which a record is used composed of an endless, flexible steel band having on its edge a magnified reproduction 5 of the sound waves, the band being strung over pulleys whereby it is moved under the sound-reproducing needle.

The invention consists in the provision of a coiled record band and of a double-pulley 10 whose one part is used for guiding the band from the inside to the outside of the coil.

By this arrangement a record of considerable length can be employed without detrimentally affecting the feeding of the band 15 and without involving difficulties in the exchange of bands.

The invention is illustrated in the accompanying drawings by a perspective view of the talking machine.

20 The record is taken on an endless band 6 of polished steel into the edge 8 of which a magnified reproduction of the sound-waves is engraved by etching or the like. The band is coiled and strung on horizontal, distanced 25 pulleys whereby it is fed for vibrating the sound-reproducing needle, the pulleys being mounted in ball-bearings. One pulley 3, which drives the the band, is arranged on a level with a guide pulley 2. A third pulley 30 4 is superposed on and connected to the pulley 3. This latter pulley serves to guide the band 6 from the inside to the outside of the coil, as shown in the drawings. Deflecting 35 rollers 7 and 7' are employed for preventing contact of the transferred stretch with the rest of the coil at the crossing point. There is also a pulley 5 connected to the pul-

ley 3 for transmitting motion to the same in any desired manner.

The pulleys are mounted on a base 1 which 40 also carries the sound-box 9. The vibrations are not picked up direct by the needle but by a blade spring 10 which bears against the edge 8 of the band at a point where the single stretch passes round the pulley 4, the 45 latter being made sufficiently narrow to enable the band to project above it. The sound-box is held horizontally between pivot points 12 and 12' so that it can rock in a vertical plane. A spring 13 pulls the box 50 and holds the needle point against the blade spring 10 so as to transmit the vibrations of the latter to the sound-box diaphragm. The trumpet 11 is connected to the sound-box in the usual manner and is guided in a yoke 14. 55

I claim:—

In a talking machine of the character described, the combination with a sound reproducing needle and with a record carrier composed of an endless travelling steel band 60 having the record on one edge, of a pair of distanced supporting pulleys on which the band is wound so as to form a coil having a plurality of strands, a deflecting pulley arranged coaxially with and connected to one 65 of said supporting pulleys so that it can be used for transferring the band from the inside to the outside of the coil, said deflecting pulley being made narrower than the band so that the record edge of the latter 70 will be held in a projecting position relative to the same, for contact with the needle.

ISAAK JACOBSON.
